UNITED STATES PATENT OFFICE.

FRANK E. TEN EYCK, OF AUBURN, NEW YORK, ASSIGNOR TO AIR DEVICE MANUFACTURING COMPANY, OF CHICAGO, ILLINOIS, A CORPORATION OF MAINE.

AUTOMATIC VALVE FOR COMPRESSED-FLUID STARTING MECHANISM.

1,184,271.

Specification of Letters Patent.

Patented May 23, 1916.

Application filed May 12, 1915. Serial No. 27,513.

To all whom it may concern:

Be it known that I, FRANK E. TEN EYCK, a citizen of the United States, residing at Auburn, in the county of Cayuga and State 5 of New York, have invented certain new and useful Improvements in Automatic Valves for Compressed-Fluid Starting Mechanism; and I do hereby declare the following to be a full, clear, and exact description of the invention, such as will enable others skilled in the art to which it appertains to make and use the same.

My invention consists in the novel features hereinafter described, reference being 15 had to the accompanying drawing which illustrates several embodiments of my invention, selected by me for purposes of illustration, and the said invention is fully disclosed in the following description and 20 claims.

Referring to the said drawing, Figure 1 represents a side elevation of an internal combustion engine and compressed fluid starting mechanism therefor, each cylinder 25 of the engine being provided with one of my improved automatic air inlet valves. Fig. 2 is a vertical sectional view of one of the valves. Fig. 3 is a similar view showing a slightly modified form of valve. Fig. 4 is a 30 similar view showing a further modification. Fig. 5 is a detail of the lower part of the valve shown in Fig. 2, illustrating a slightly modified construction.

My present invention relates to an automatic inlet valve adapted particularly for use in connection with a compressed air starting system for internal combustion engines, and in order to make the construction and operation of my improved valve clear, I 35 have shown, in Fig. 1, one form of apparatus for starting an internal combustion engine by means of compressed fluid in which my improved valve is used, the general features of the apparatus so disclosed in Fig. 40 forming the subject matter of my former application for Letters Patent of the United States, filed on or about April 20, 1915, and given Serial No. 22,551, and being therein particularly claimed.

50 Referring briefly to said Fig. 1, 1 represents the internal combustion engine provided with cylinders 2, 3, 4, and 5. 9 represents a pump or compressor operatively connected with the engine shaft and capable 55 of being actuated by the engine when the

latter is running, to compress air which passes through a pipe 18 and through a controlling valve 60, mounted on a steering head and controlled by a hand lever 72, adjacent to the steering wheel, the compressed air passing from the valve 60 through a pipe 80 to a storage tank, indicated at 19. The compressed air from the tank may be transmitted by the proper operation of the valve 60 through a starter pipe line 38 to a distributor 22 mounted on the pump and by connections with the engine, from which it passes by a series of distributing pipes 2^a, 3^a, 4^a, and 5^a, to one of my improved automatic inlet valves 93. In the construction shown in Fig. 1, the connection between each of these inlet valves and the adjacent engine cylinder is through the spark plug aperture which is provided with a fitting 91 to receive a spark plug 90, and also the inlet valve 93, 75 and in this instance the said fitting is provided with a threaded portion 91^a, see Fig. 2, upon which the inlet valve is screwed. In the form of my invention shown in Fig. 2, this inlet valve comprises a cylindrical body 80 having between its ends a reduced central aperture 93^a communicating with the cylindrical chamber 93^b at the upper end of the cylindrical body, and a chamber 93^c at the lower end thereof, and a valve seat 94 is 85 provided at the lower end of this neck or reduced aperture to receive a conical valve 95 formed upon the lower end of or secured to a valve stem which is provided with a guiding portion 95^a having a sliding engagement with the reduced passage 93^a, the valve stem being reduced between said guiding portion and the valve 95, so as to form an annular passage surrounding the valve stem within the passage 93^a, at which point the 95 valve casing or body is provided with an inlet aperture 104 into which one of the distributing pipes for the compressed fluid, as 2^a, 3^a, 4^a, etc., is attached. The upper part of the valve stem is provided with a piston member 96 which is preferably provided with an integral body 96^a of slightly less diameter than the chamber 93^b, and this body is secured to the upper end of the valve stem by a threaded connection, in this instance the said body being provided with a threaded recess to receive a threaded extension 95^b of the valve stem. On the exterior of the reduced body portion 96^a, I provide a sliding piston ring, 102, and between the pis- 100

ton ring and the piston head 96, I provide a ring of compressible packing 103. Within the chamber 93^b I also provide a spring 101 which bears at one end against the bottom of the chamber and at its upper end against the piston ring 102 so that this spring performs two functions, to wit, that of holding the valve 95 firmly up against its seat, and also that of compressing the packing 103 between the ring 102 and the piston head 96.

10 The upper end of the valve body is closed and provided with a suitable inlet aperture, and in this instance, I have shown it provided with a cap 98 screwed onto the valve body and provided with a passage 99 extending transversely through the same and through a threaded connection 90^a at either side of the cap, and the passage 99 is connected by a vertical passage 100 with the chamber 93^b directly above the piston head 96.

15 The upper end of the valve is adapted to be connected with the source of compressed fluid at the same time that compressed fluid is admitted to the inlet aperture 104 so that the accumulated pressure will first be exerted on the head of the piston 96 and caused to open the valve 95, thereby admitting the compressed fluid entering at the aperture 104 to the chamber 93^c and thence to the cylinder of the engine. As indicated in Fig. 1, the several inlet valves have their threaded extensions 90^a connected by pipes 105, and with a by pass indicated at 107 which leads to the controlling valve 60 or to the starter pipe line 38 either directly or through said controlling valve, so that when air is admitted to the starter pipe line 38, it will also pass through the by pass 107, 20 and thence to the piston cylinder of each of the automatic valves, so as to open the valves and permit the flow of compressed fluid thereto under the control of the distributor, as fully set forth in my prior application above referred to. In this form of the valve, it will be noted that the movement of the valve to close is in an outward direction so that pressure within the cylinder tends to close the valve and the pressure in the by pass leading to the upper end of the valve overcomes the resistance of the spring 101 in opening the valve at a time when there is no pressure within the cylinder.

25 In Fig. 3 I have shown a slight modification of my improved valve. In this instance the valve body is formed in two parts 35 and 36 preferably screwed together, although the body might be formed in a single piece, if preferred. The lower end of the valve body is provided with a valve seat 37 which receives the valve 34 on the lower end of a valve stem 34^a which is of smaller diameter than the chamber within the lower part of the valve casing, and this

part of the valve casing is provided with an inlet 104^a to receive a pipe conveying fluid pressure to the cylinder. The upper end of the lower portion of the valve body is provided with means for guiding the valve stem 34^a, in this instance a threaded sleeve 39 screwed into the part 36, and the upper end of the valve stem is provided with a piston head 40, detachably secured thereto, preferably by screw threaded connections, 75 and having a reduced body portion 41, piston ring 42, and packing 43. The upper end of the cylindrical part 35 of the valve body is closed in this instance by a plug 44 and a coil spring 45 is interposed between the plug 44 and the piston ring 42, thereby holding the valve 34 on its seat and also serving to compress the packing 43. The upper portion of the valve body is provided with an inlet 90^b having a threaded extension 90^c to which a by pass from the air inlet pipe can be connected for the purpose of raising the piston 40 against the compression of the spring 45 to open the valve 34 and admit fluid pressure to the cylinder. In this form of the valve the valve proper opens in a direction away from the cylinder and the spring 45 must be of sufficient tension to hold the valve closed under conditions of normal pressure 95 within the cylinder.

30 Fig. 4 represents a slightly modified form of the valve shown in Fig. 3 in which the lower body portion 36^a is provided with a recess 36^b communicating by short passage 100 36^c with the interior of the valve casing, and adapted to receive a threaded plug valve 33 provided with a conical valve portion to close the passage 36^c and having a longitudinal passage 32 extending to a reduced portion of the valve plug at its inner end and communicating with a funnel-shaped recess 31 at the outer end of the valve plug. The object of this auxiliary passage and plug is to permit the admission, when desired, of 110 liquid fuel for priming purposes and this can be accomplished readily by slightly unscrewing the valve plug 33 and pouring a small quantity of the liquid fuel in the aperture 31 so that it will be carried into the 115 cylinder when the valve 34 is open. The other features of construction shown in this figure, are identical with those shown in Fig. 3.

35 The form of valve shown in Fig. 2 may 120 also be provided with a priming arrangement, and in Fig. 5 I have shown the lower portion of the valve, here designated at 93^d, provided with an extension 36^d having a recess therein, communicating by a passage 125 36^e with the interior of the valve casing, in this instance below the valve indicated at 95^c. The recess in the extension 36^d is provided with a plug valve 33^a having a reduced portion and conical valve at its in- 130

ner end to close the aperture 36^a and provided with a longitudinal passage 37^a extending from the exterior recess 31^a to the lateral surface of the reduced portion for 5 the admission of liquid fuel.

In the forms of my improved valve herein shown and described, the piston is secured to the valve stem detachably, the stem being preferably provided with threaded portions, as shown, which screw into a threaded recess in the piston body and by this means the ready assemblage of the various parts can be effected. This is convenient, in any case, but is particularly desirable where the valve proper is of greater diameter than the passage between the lower chamber of the valve casing and the piston cylinder at the upper end of the same. 10 15

While I have shown my improved valve 20 as having its outlet passage leading directly into one of the cylinders of the explosive engine, I do not limit myself to the use of the valve in connection with the cylinder of the engine itself, as it might be employed 25 in connection with the cylinder or cylinders of a compressed fluid motor or a combined pump and motor, by making the proper pipe connections therewith.

What I claim and desire to secure by Letters Patent is:—

1. In a compressed air starting mechanism for internal combustion engines, an automatic inlet valve comprising a valve casing provided with a main compressed air 35 inlet, an air outlet, and a valve interposed between said air inlet and outlet, said casing being also provided with a valve actuating cylinder having an auxiliary compressed air inlet separate from said main inlet, a piston 40 in said cylinder, connected with said valve, and provided with a head fitting said cylinder and with a reduced portion adjacent thereto, a ring having a sliding engagement with said reduced portion, packing interposed between said piston head and said ring, and a spring engaging said ring for holding the valve in one position, and compressing said packing. 45

2. In a compressed air starting mechanism for internal combustion engines, an automatic inlet valve comprising a valve casing provided with a main compressed air inlet, an air outlet, and a valve interposed

between said air inlet and outlet, said casing being also provided with a valve actuating cylinder, provided with an auxiliary compressed air inlet separate from said main inlet, a piston in said cylinder, connected with said valve, and provided with a head fitting said cylinder and with a reduced portion adjacent thereto, a ring having a sliding engagement with said reduced portion, packing interposed between said piston head and said ring, a spring engaging said ring for holding the valve in one position, and compressing said packing, and a priming device connected with said valve casing between the said main inlet and the outlet thereof. 55 60 65

3. In a compressed air starting mechanism for internal combustion engines, an automatic inlet valve comprising a valve casing provided with a main compressed air inlet, an air outlet, a valve interposed between said air inlet and outlet, said casing being also provided with a valve actuating cylinder having an auxiliary compressed air inlet separate from the said main inlet, a piston in said cylinder, connected with said valve, and provided with a head fitting said cylinder and with a reduced portion adjacent thereto, a ring having a sliding engagement with said reduced portion, packing interposed between said piston head and said ring, a spring engaging said ring for holding the valve in one position, and compressing said packing, said valve casing being provided with a priming passage communicating at its inner end with the interior of the casing between the main inlet and outlet thereof and having a threaded recess at its outer end, a threaded plug for engaging said recess, said plug provided with a longitudinal liquid passage extending to a point near its inner end, and also having a valve at its inner end for closing said priming passage, whereby by slightly unscrewing said plug liquid fuel may be introduced into said priming passage through said plug. 80 85 90 95 100

In testimony whereof I affix my signature in the presence of two witnesses.

FRANK E. TEN EYCK.
